UNITED STATES PATENT OFFICE.

HOBERT J. HURD, OF BRIDGEPORT, CONNECTICUT.

CARTRIDGE-SIZING MACHINE.

No. 887,809.

Specification of Letters Patent.

Patented May 19, 1908.

Application filed April 10, 1905. Serial No. 254,746.

To all whom it may concern:

Be it known that I, HOBERT J. HURD, a citizen of the United States, and a resident of Bridgeport, in the county of Fairfield and State of Connecticut, have invented certain new and useful Improvements in Cartridge-Sizing Machines, of which the following is a specification.

My invention relates to machines for sizing paper tubes, and it consists in certain details of construction to be more fully set forth in the following specification.

To enable others to understand my invention reference is had to the accompanying drawings in which:

Figure 1—represents a side elevation of the machine: Fig. 2—is an upper plan view: Fig. 3—is a rear end elevation looking in the direction of arrow *a* of Fig. 2: Fig. 4—is an enlarged sectional view of the bed of the machine and hopper on line *b b* of Fig. 2: Fig. 5—is an enlarged upper plan view of the tube arbor carrying slide, broken view of the tube-arbors, machine-bed, and rocking-frame adapted to actuate or slightly change the position of the tube-arbors for the purpose of ejecting a finished tube: Fig. 6—is an enlarged detail view of the gear for operating the tube-arbor carrying slide; sectional view of the shaft on which said gear is mounted; sectional view of the pinion-shaft adapted to actuate said slide, and broken view of the driving-shaft: Fig. 7—is an enlarged detail cross sectional view of one of the tube carrying arbors: Fig. 8—is an enlarged cross sectional view of the arbor carrying slide and rocking-frame, also a side elevation of the pawl carrying slide and pawl, also a sectional view of the arm for tilting the pawl, sectional view of the support for said arm on line *c c* of Fig. 2; also a rear end elevation of the tube-arbor carrying shaft and dial therefor, showing the pawl disengaged from said dial and said shaft in the act of being rotated: Fig. 9—is a view similar to Fig. 8 except that the pawl is engaged with the dial to throw the tube-arbors slightly out of horizontal alinement with each other for the purpose of ejecting a sized tube: Fig. 10—are two circles representing the tube-arbors thrown out of horizontal alinement: Fig. 11—is an enlarged broken view of one of the tube arbors and tube, also an enlarged sectional view of the sizing die, said arbor shown as being thrown out of the center line of the die to

bring the end of said tube against the inner face of the die for the purpose of ejecting the tube when the arbor retreats: Fig. 12—is an enlarged detail front elevation of the tube-sizing die and chuck for holding same: Fig. 13—is an enlarged cross sectional view of the tube-sizing die, its chuck, and hollow spindle on which said chuck is mounted: Fig. 14—is an enlarged broken view of one of the tube-arbors and tube thereon, side elevation of spring actuated slides adapted to be opened by the forward end of a tube-arbor to permit the end of the tube to engage the face of said slides to force said tube on to the arbor: Fig. 15—is an enlarged detail front elevation of the spring actuating slides shown at Fig. 14: Fig. 16—is an enlarged rear end elevation of the arbor carrying slide; tube-arbor carrying shaft and its dial; dial actuating pawl and its slide, broken view of the pin adapted to carry a roll on its forward end to engage one of the cam-grooves in said shaft, and broken view of the operating-lever for said pin: Fig. 17—is an enlarged detail plan view of the arm for tilting the pawl connected with the dial of the tube-arbor shaft.

Its construction and operation are as follows:

1 represents the bed of the machine. 2 is a slide adapted to be longitudinally reciprocated thereon.

3, Figs. 1—2, is the driving-shaft journaled in the bearings 4. 5 is the driving-pulley mounted on one end of this shaft, and 6 is a pinion mounted on the other end to register with and rotate the large gear 7 mounted on the cross-shaft 8.

9 is a cam-shaft on the opposite side of the machine which is rotated through the medium of its bevel-gear 10 registering with the bevel-gear 11 of said cross-shaft.

The slide 2 is reciprocated by means of the pinion 12 on the shaft 13, Fig. 6, alternately engaging with the internal segmental teeth 14 and 15 formed on the large gear 7. This shaft 13 is journaled in the bearing 16, shown at Figs. 2 and 3. 17 is a pinion on the inner end of this shaft registering with the rack 18 on the underside of the slide 2, see also Figs. 1 and 3.

Referring to Fig. 6, the gear 7 runs continuously in the direction shown by the arrow, and pinion 12 is just being engaged by the teeth 14 for a forward movement of the arbor carrying slide.

105

110

19 and 20 are pins projecting laterally from the inner vertical face of the pinion 12 so that, when the teeth 14 have passed by the said pinion, one of these pins will engage 5 with the cam 21 to reverse the rotation of said pinion in order that it may properly register with the outer series of teeth 15 on the gear 7. By the time that the pin engaging the cam 21 has passed through said 10 cam, the other or opposite pin will engage the cam 22. In traversing from cam 21 to cam 22, the rotation of the pinion will cease temporarily and, consequently, the slide will be halted in its advanced position for 15 the purpose presently to be described. The throw of the cam 22 is such that the rotary travel is increased to correspond with the travel of the teeth 15 so that there will be no shock when said teeth engage the pinion 20 for a reverse movement of the slide. When, therefore, the cam 23 engages one of the pinion pins, its rotary motion is again reversed in readiness to be engaged by the teeth 14, and the cam 24 will time the rotary travel of the pinion to agree with the speed 25 of said teeth.

25, Figs. 2, 3 and 5, is a standard secured to the forward end of the slide 2, and, in said standard, is journaled the shaft 26. 27 is a 30 head mounted on the forward end of this shaft carrying the tube-arbors 28 and 29.

30, Figs. 2, 4, 12 and 13, is the die-head carrying the sizing-die 31, and it is mounted on the hollow spindle 32 journaled in the 35 uprights 33. 34 is a pulley mounted upon said spindle to give it a rotary movement independent of the rotary movement of the driving-shaft 3, previously mentioned.

35 is a hopper for holding the unsized 40 tubes 36, Fig. 4, which hopper is supported on the bracket 37 projecting from the machine-bed. 37^a, see also Fig. 2, are projections of said bracket in which is journaled the short shaft 38, on which is mounted the 45 tube carrying flanges 39 having the grooves 40 adapted to receive the unsized tubes in the hopper and carry them outside in line with one of the tube-arbors, for the purpose presently to be explained. The shaft 38, 50 with its tube carrying flanges 39, is intermittently rotated through the medium of the ratchet-wheel 41 mounted on said shaft and the lever 42 journaled on the driving-shaft 3, the upper end of which lever carries 55 the pawl 43 adapted to engage the teeth of said ratchet-wheel. 44 is a vertical rod actuated by the spring 45 to maintain the engagement of the pawl 43 with the said ratchet-wheel. The lever 42 is actuated by 60 the forked-lever 46 carrying the roll 47 adapted to engage with the cam-groove 48 of the disk 49 mounted on the cam-shaft 9.

The enlarged portion 26^a, Fig. 5, of the arbor carrying shaft 26 is provided, see also 65 Figs. 1, 2, 3, 8, 9 and 16, with cam-grooves

50 and 51 adapted to be alternately engaged by the roll 52, Fig. 5, and thus rotate said shaft one-half of a revolution for the purpose presently to be described. This roll is mounted on the end of the reciprocating-pin 70 53 operatively mounted in the standard 54 mountee on the rear end of the machine-bed 1. This pin is pivotally connected to the upper end of the lever 55, the lower end of which lever carries, Fig. 3, the roll 56 to engage the cam 57 mounted on the shaft 9. The central portion of said lever is pivotally supported on the body portion of the screw 58. 75

60 is a dial carried by the shaft 26, and 61 are notches in its periphery adapted to be 80 alternately engaged by the pawl 62 pivotally supported on the screw 63 projecting from the slide 64, which slide is operatively mounted in a part of the standard 25. 65 is a pin in the outer end of this slide carrying 85 the roll 66 adapted to travel in the groove or channel-way 67 on the upper surface of the frame 68, as shown at Figs. 8 and 9. This frame is mounted on the rock-shaft 69, seen more clearly in Fig. 1, which shaft is journaled in the bearings 70 secured to the machine-bed, 71 is an arm secured to this shaft and carries at its lower end the roll 72 adapted to engage a cam-groove, not shown, in the vertical face of the disk 73 mounted on 90 the shaft 9 so that, through the medium of said cam, the shaft 69 is oscillated to move the frame 68 to and from the bed of the machine for the purpose to be hereinafter more fully described. 95

74, Figs. 1, 3, 16 and 17, is an arm whose shoulder is pivotally supported by one end to the lever 55, while the fore-arm, see also Figs. 2, 5, 8 and 9, is adapted to rest on the gib 75 and be moved forward to engage the outer 105 end 62^a of the pawl 62 and carry the forward end of said pawl out of engagement with the dial 60, and, when disengaged therefrom, said pawl will be reengaged with the lowest notch of said dial by means of the spring 76 110 shown at Figs. 8 and 9.

Operation: In Fig. 2, the slide is in the act of moving forward with the arbor 28 empty, and the arbor 29 carrying the unsized tube 36^a. In the meantime, the tube carrying 115 flanges 39 have brought the tube 36^b directly in the path of the approaching arbor 28 so that, while the sizing die is engaged with the tube on the arbor 29, the arbor 28 will enter the tube 36^b, passing entirely 120 through the same. Back of this tube are, see also Figs. 14 and 15, the two vertical slides 77 and 78, which slides operate in the guide-way 79 of the bracket 80. The inner ends of these slides are slightly concaved to 125 form the opening 81 shown at Fig. 15. The forward end of the tube 36^b will lie in close proximity to the outer faces of these slides so that, when the arbor 28 enters said tube, these slides will act as a kicking-post to force 130

the tube on to the arbor. To insure the tube being forced on to the arbor far enough, and also to prevent the end of the arbor striking against a solid body, the rounded end of the 5 arbor will enter the opening 81 and force the slides 77 and 78 back against the tension of their springs 82 and 83, and thus permit the end of the arbor to pass between said slides while the end of the tube is still in pushing 10 contact therewith. When, therefore, a tube from the hopper has been forced on to one of the arbors, the tube on the other arbor will have been sized by contact with the rapidly rotating die 31.

15 The finished tube is stripped from its arbor in the following manner: That portion of the arbor which supports the paper tube is, of course, the same in diameter as the internal diameter of the tube, or, at least, near enough 20 to said internal diameter to insure a close fit, while that portion of the arbor not adapted to enter the tube is larger in order to form the shoulder A, Figs. 7 and 11, to serve as a kicking-post against the action of the sizing-die, 25 or, in other words, as a means for pushing the tube through the sizing-die. The lower portion of this enlarged part of the arbor is cut away as shown at B, which cut-away portion is on a line with the arbor proper.

30 After the tube has passed through the sizing-die, the slide 2 will continue to advance so as to carry the rear end of the sized tube just beyond the inner straight face 31^a of the sizing-die. While this extra forward movement is taking place, the rock-shaft 69 will 35 be actuated by its cam to throw the frame 68 slightly toward the machine, and by reason of the engagement of the slide 64, Fig. 9, with this frame, as before mentioned, the 40 said slide will be carried inward with said frame sufficient to rotate the arbor 26 and thus throw the tube-arbors slightly out of horizontal alinement with each other as represented by the diagram shown at Fig. 10, 45 wherein the dotted line C represents the line on which the centers of the two arbors would lie before being tilted. This slight tilt of the arbors will, see Fig. 11, also throw the arbor in the sizing-die out of center with said die 50 with the cut-away portion B of the arbor resting on the lower surface of the die. This will bring the lower edge of the finished tube 55 against the inner straight face of the sizing-die and thus hold the tube while the arbor is withdrawn therefrom by the now retreating slide 2.

When the slide 2 has retreated far enough to insure the removal of the sized tube, the slide 64 will be carried out so as to level up 60 the arbors, or, in other words, bring them into the same horizontal alinement they occupied previous to the tilting movement before described. Immediately after this movement, the lever 55 will be actuated forward 65 to place the roll 52 in the path of one of the

cam-grooves 50 or 51, as the case may be, and, also, the arm 74 in the path of the outer end 62^a of the pawl 62. This outer end of the pawl will ride up on the arm 74, see Fig. 8, to disengage the forward end of said pawl 70 with the dial 60, so as to leave the arbor carrying shaft free to make one-half of a revolution when one of the cam-grooves engage with the roll 52, Fig. 5. This movement will have rotated the tube carrying arbors to 75 bring the one, on which a tube has been forced, in line with the sizing-die, and the empty arbor in position to receive a fresh unsized tube. When the slide starts forward, the lever 55 is retreated to carry the roll 52 out 80 of the cam-groove in the arbor carrying shaft, and the arm 74 from under the outer end of the pawl 62 so as to let said pawl reengage with the lowest notch in the dial 60, as seen at Fig. 16.

85 At the inner end of each of the cam grooves 50 and 51 of the shaft 26, is a straight portion 50 to serve as a "standstill" to enable the roll 52 to be fully retreated when the slide 2 begins its forward movement. One of these "standstill" portions, 84, is shown at Fig. 1.

Having thus described my invention what I claim as new and desire to secure by Letters Patent is:

1. The combination, in a paper tube sizing 95 machine, of an intermittently rotatable shaft having a head with a plurality of tube-arbors projecting therefrom, a longitudinally reciprocating support for said shaft, a rotatably supported sizing-die, said shaft having spiral 100 grooves formed in its rear end, means for alternately engaging said grooves whereby said shaft is partially rotated, for the purpose set forth.

2. The combination, in a paper tube sizing 105 machine, of an intermittently rotatable head carrying a plurality of tube arbors, a rotatably supported sizing-die, suitable means for reciprocating said head and its arbors to and from said die, suitable means for throwing 110 the arbor, carrying a finished tube, out of center with said die to bring the rear end of said tube in contact with the rear edge of the die to strip said finished tube from its arbor when said arbor is being retreated, for the 115 purpose set forth.

3. In a paper tube sizing machine, a paper tube carrying arbor, a rotatably supported sizing-die, suitable means for tilting the arbor for the purpose of ejecting a finished tube 120 . therefrom, for the purpose set forth.

4. In a paper tube sizing machine, an intermittently rotatable head carrying a plurality of arbors, a rotatably supported sizing-die, the axial lines of said die and head eccentrically located with respect to each other, a reciprocating slide carrying said head, a hopper for unsized tubes, a rotatable tube-carrier to receive the unsized tubes from said hopper and carry it in line with an empty arbor so 130

that, when one tube is being sized, on one arbor, an unsized tube is being forced on the other arbor, for the purpose set forth.

5. The combination, in a paper tube sizing machine, of a reciprocating slide, a support thereon, a shaft journaled in said support, a head thereon, tube carrying arbors projecting from said head, cam grooves in said shaft, a rotatably supported sizing-die, the axial line of said die and shaft eccentrically located with respect to each other, a hopper for unfinished tubes, a rotatable tube-carrier to deliver tubes from the hopper in line with one of said arbors, while the other arbor, having 10 an unsized tube thereon, is in axial alignment with the sizing-die so that, when said slide is moved forward, a tube will be sizing on one arbor, while an unsized tube is being forced on to the other of said arbors, means 15 for slightly rotating said shaft, after a tube has been sized, to bring the rear end of the sized tube against the rear edge of the die and cause the sized tube to be ejected from its arbor when said arbor is being retreated, 20 means for bringing said arbor central with the die after the finished tube has been ejected therefrom, means for partially rotating said shaft to reverse the positions of said arbors, 25 for the purpose set forth.
- 30 6. In a paper tube sizing machine, a sizing die, a tube carrying arbor having a shoulder partially cut away, said shoulder adapted to support the rear end of a tube while said tube is being sized, means for imparting a slight 35 lateral movement to the arbor, after the tube has passed through the die, so as to bring the unsupported end of the tube against the rear face of the die and thus provide means for the ejection of the tube from the arbor when said 40 arbor is retreating, for the purpose set forth.
7. In a paper tube sizing machine, a longitudinally reciprocating slide, a support therefor, a support on said slide, an intermittently rotatable shaft journaled therein, 45 a head carrying a plurality of tube arbors on one end of said shaft, the other end of said shaft having cam grooves, a rotatably supported sizing-die, a hopper, a rotatable tube-carrier adapted to receive tubes from said 50 hopper, means for operating said slide to simultaneously carry one arbor into an unsized tube, and the other arbor, bearing an unsized tube, into the sizing-die, means for temporarily placing the axial lines of such 55 arbor and the die eccentrically with respect to each other for the purpose of ejecting a finished tube when the slide is retreated, automatic means for righting said arbor before the completion of the return movement of the slide, automatic means adapted 60 to engage the cam grooves of said shaft to reverse the positions of said arbors, for the purpose set forth.
8. In a paper tube sizing machine, a reciprocating slide carrying an intermittently 65

rotatable shaft journaled thereon, means for operating said slide, a plurality of tube arbors connected with said shaft and located at one side of the axial line of the shaft, a dial carried by said shaft, a pawl adapted to be engaged with said dial or disengaged therefrom, said shaft having cam grooves in its rear end, movable means adapted to lie in the path of the pawl, when the slide is retreating, and release the same from the dial 70 and temporarily hold it out of contact therewith, movable means projected in line with one of said grooves when the shaft is released to cause said shaft to partially rotate, for the purpose set forth.

9. In a paper tube sizing machine, a reciprocating slide carrying an intermittently rotatable shaft journaled thereon, tube arbors connected with said shaft and at one side of the center thereof and diametrically opposite each other, a rotatably supported sizing-die, a hopper, a carrier to deliver unsized tubes therefrom, means for locking the shaft, means for operating said slide to carry one arbor and its tube into the sizing-die simultaneously with the forcing of the other arbor into an unsized tube, means for slightly rocking the shaft for the purpose of stripping the finished tube from its arbor, means for restoring the shaft to its normal position 90 after the arbor has been withdrawn from the sizing-die, means for temporarily unlocking the arbor near the completion of the return movement of the slide, and means for partially rotating the shaft after it has been unlocked to reverse the positions of the arbors, for the purpose set forth.

10. In a paper tube sizing machine, a tube arbor carrying shaft rotatably mounted on a movable support, a dial on said shaft, a pawl mounted on a movable support to engage therewith, a rotatably supported sizing-die adapted to receive said arbor with an unsized tube thereon, means for imparting a slight rocking movement to said shaft through the medium of said pawl to throw the arbor out of center with the sizing-die for the purpose of stripping the finished tube from its arbor, for the purpose set forth.

11. In a paper tube sizing machine, a tube-arbor carrying shaft, a movable support on which said shaft is rotatably mounted, a dial on said shaft, a movable support, a pawl pivotally mounted thereon and adapted to engage with said dial, means for automatically imparting a slight rotary movement to the shaft through the medium of the pawl, for the purpose set forth.

12. In a paper tube sizing machine, a slide, a tube carrying shaft rotatably mounted thereon, means for locking said shaft against rotation and temporarily unlocking the same, a rack on the underside of said slide, a cross-shaft carrying a pinion meshing with said rack, a driving-shaft, carrying 125

pinion 6, continuously running gear 7 mounted on the cross-shaft 8, and registering with pinion 6, said gear having segmental teeth 14 and 15, cams 21, 22, 23 and 24, pinion 12 having pins 19 and 20 adapted to engage said cams to reverse said pinion, said pinion adapted to alternately engage teeth 14 and 15 to reciprocate said slide, for the purpose set forth.

10 13. In a paper tube sizing machine, a rotatably supported sizing-die, a reciprocating slide, an intermittently rotatable shaft, tube arbors connected therewith, means for locking said shaft against rotation, means for actuating said slide, a driving-shaft, a

cam-shaft, means for rotating said shaft to reverse the position of the arbors, to rotate said shaft to carry an arbor out of center with the sizing-die, and means for temporarily unlocking said shaft through the 20 medium of the cam-shaft, for the purpose set forth.

Signed at Bridgeport in the county of Fairfield and State of Connecticut this 5th day of April, A. D. 1905.

HOBERT J. HURD.
